UNITED STATES PATENT OFFICE.

FREDERICK W. STEWART, OF BEAVER, PENNSYLVANIA.

GLASS-PRESSING MACHINE.

1,343,987.

Specification of Letters Patent. Patented June 22, 1920.

Application filed October 27, 1915. Serial No. 58,221.

To all whom it may concern:

Be it known that I, FREDERICK W. STEWART, a citizen of the United States, and resident of Beaver, in the county of Beaver 5 and State of Pennsylvania, have invented a new and useful Improvement in Glass-Pressing Machines; and I do hereby declare the following to be a full, clear, and exact description thereof.

10 My invention relates to machines for pressing glass blanks preparatory to blowing, or for forming the finished article by pressing where desired.

15 The object of my invention is to provide for the automatic control of the press-head, and the time that the fluid pressure is kept on the press-head cylinder, and the plunger held in contact with the glass. A device of this character when once adjusted works 20 without attention on the part of the operator except in emergency, whereupon provision is made for cutting out the automatic feature and holding the plunger in its raised position until the difficulty has been 25 corrected.

In the accompanying drawings, Figure 1 is a side elevation of my improved machine; Fig. 2 is a plan view of the mold-table and the automatically operated valve; Fig. 3 is 30 a section on the line 3—3, Fig. 1; Fig. 4 is a view of the pipe connections; Fig. 5 is a sectional view of the triple valve; and Fig. 6 is a section on the line 6—6, Fig. 4.

Referring to the drawings, the numeral 35 2 designates a suitable frame or carriage mounted on wheels 3 for convenience in transporting the device from one part of the factory to another.

A motor 4 is mounted on the carriage. A 40 pinion 5 on the motor-shaft meshes with the gear-wheel 6 on the counter-shaft 7 mounted in bearings 8. A worm 9 on the counter-shaft 7 meshes with the worm-wheel 10 on the vertical shaft 11 stepped in bearings 12. 45 Mounted on the shaft 11 is the arm 13 provided at its outer end with the stud 14. Above the arm 13 on the shaft 11 is the disk 15 which is cut away as at 16. The disk 15 carries the cam 17, which may be secured 50 thereto in any suitable manner. This cam is made up of two plates 17^a and 17^b, the one slidable with reference to the other. The inner plate 17^a has the slot 17^c, and a bolt on plate 17^b engages said slot to secure 55 the plates rigidly together.

A rotary mold-table 18 is mounted on the

sleeve 19 on the shaft 20. On the sleeve 19 is the star-wheel 21 with the slots 22. This star-wheel with the arm 13 forms what is commonly known as the Geneva movement. 60

The molds 23 are mounted on the table 18, and said molds support the partible neck-rings 24.

A cylinder 25 has the sleeves 26, which engage the columns 20 and 27, and said cylinder is adjustable by means of the nuts 28 engaging the threaded portions 29 of said columns. The cylinder 25 contains an ordinary piston connected up to the piston-rod 30, which carries the plunger-frame 31 of 70 ordinary construction. At the lower end of the plunger-frame 31 is the plunger 32.

The pipes 33 and 34 lead to the upper and lower ends respectively of the cylinder 25. These pipes have the flexible sections 75 35, which connect the pipes 33 and 34 with the pipes 36 and 37. Pipes 36 and 37 are connected up to the triple-valve 38. The supply-pipe 39 is connected up to the valve 38. 80

The handle 40 of the valve projects into the path of the cam 17 so as to be engaged thereby as the disk 15 rotates. Springs 41 and 42 are connected to stationary members 43 and 44 respectively, and the opposite ends 85 of said springs are connected to the opposite ends of the arm 45, and act to throw the handle 40 back to the normal position and admit air to the lower end of the cylinder 25 to lift the plunger as fully herein- 90 after set forth.

Located in the supply-pipe 39 and in the pipe 37 are the valves 46 and 47 respectively. A common lever 48 is connected to said valves so that they may be operated 95 simultaneously for the purpose fully hereinafter set forth.

Mounted on the shaft 7 is the brake-wheel 49. A foot-lever 50 is fulcrumed at 51 in suitable bearings, the outer end of said lever having the curved portion 52, which is adapted to engage and conform to the periphery of the brake-wheel 49. The spring 53 is interposed between the outer end of the lever 50 and the support 54, said 100 spring tending to lift the outer end of said lever and release the brake-shoe 52. A chain 55 is connected to the lever 50 and to a suitable switch 56. By operating the lever 50, the brake-shoe 52 is applied to the brake-wheel 49, in case of an emergency, to stop 110 the machine and, at the same time, the switch

56 operates to cut off the current to the motor.

In the operation of the machine, the glass for making the blank or article to be pressed is gathered in the ordinary manner, and deposited into one of the molds 23. The mold then moves around in position under the plunger 32 by the intermittent action of the Geneva movement. The 10 operation of the disk 15 is so timed that when the mold has been brought into proper position under the plunger, the arm 40 of the valve is engaged by the cam 17 and upon the further movement of the disk 15, 15 the engagement of the cam with the arm 40 moves the arm into the position indicated in dotted lines, Fig. 5. This acts to bring the pipe 37 into communication with the exhaust while the air pressure is admitted to the pipe 36 and passes thence to the upper end of the cylinder 25. The plunger 32 is accordingly lowered into the mold and the time that the plunger is permitted to remain in contact with the glass 25 is controlled by the size of the cam 17 or the length of time the arm 40 of the valve remains in contact therewith. This will depend upon the size of the article being pressed and the amount of glass used 30 therein. In this manner the dwell of the plunger is accurately controlled. The cam 17 is provided with the receding portion 17' which acts to gradually reverse the arm 40 or gradually close the ports communicating with the pipe 36, but when the handle 40 of the valve is released from the cam, the springs 41 and 42 complete the movement of the valve, so as to again connect the supply-pipe up with the pipe 37 leading 35 to the lower end of the cylinder 25 to lift the plunger. The Geneva movement is so timed that upon the lifting of the plunger the stud 14 enters one of the slots 22 of the star-wheel 21 and the table 18 is moved 40 to bring another mold around into position under the plunger.

If for any reason it is not desired to lower the plunger into the mold when it comes around into position, such as failure of the 45 glass to be properly deposited in the mold or the condition of the glass is bad, the operator by moving the handle 48 cuts off the supply of motive fluid and by the operation of the valve 47 simultaneously therewith traps the motive fluid in the lower end of the cylinder 25 and so holds the plunger in its raised position. This does

not interfere with the movement of the parts, as the cam 17, although engaging the handle 40, and moving the same will have 60 no effect to admit fluid to the upper end of the cylinder or release the fluid from the lower end thereof, so that while the plunger does not descend, the machine can continue to operate as before. 65

By the use of the emergency lever 50, the operator places his foot upon the treadle, throws the brake-shoe 52 into engagement with the brake-wheel 49, and stops the operation of the machine at once, while at the 70 same time, the chain 55 operates the switch 56 and shuts off the current to the motor. The arm 57 is employed for returning the switch to its closed position when the treadle has been raised by the spring 53 75 and it is desired to start the motor.

What I claim is:

1. In a glass pressing machine, the combination of a rotary table, means for intermittently rotating same, a mold on said table, a plunger, a fluid-operated cylinder for said plunger, a valve controlling motive fluid to said cylinder, fluid-supply connections leading to the upper and lower ends of said cylinder, a rotary-member, a cam on 80 said rotary-member, an arm on said valve in the path of the movement of said cam, and means independent of said valve for cutting off the supply of motive fluid to said cylinder and at the same time trapping 85 the fluid in the lower end thereof.

2. In a glass pressing machine, the combination of a rotary table, means for intermittently rotating same, a mold on said table, a plunger, a fluid-operated cylinder for said 90 plunger, a valve controlling motive fluid to said cylinder, fluid-supply connections leading to the upper and lower ends of said cylinder, a rotary-member, a cam on said rotary-member, an arm on said valve in 100 the path of the movement of said cam, a valve in the supply connection, a valve in the connection leading to the lower end of said cylinder, and means for closing the last two said valves simultaneously whereby the 105 motive fluid is trapped in the lower end of said cylinder.

In testimony whereof, I, the said FREDERICK W. STEWART, have hereunto set my hand.

FREDERICK W. STEWART.
